US00D899805S

(12) **United States Design Patent** (10) **Patent No.:** **US D899,805 S**
Tsui (45) **Date of Patent:** **** Oct. 27, 2020**

(54) **BAG DISPENSER**

- (71) Applicant: **Duratech Plastics Corporation**, Carlstadt, NJ (US)
- (72) Inventor: **Jonathan J. Tsui**, Wyckoff, NJ (US)
- (73) Assignee: **Duratech Plastics Corporation**, Carlstadt, NJ (US)
- (**) Term: **15 Years**
- (21) Appl. No.: **29/662,513**
- (22) Filed: **Sep. 6, 2018**
- (51) LOC (12) Cl. **06-06**
- (52) U.S. Cl. **USPC** **D6/518**
